UNITED STATES PATENT OFFICE.

EDWARD NUGENT, OF BROOKLYN, ASSIGNOR OF ONE-HALF TO ALGERNON K. JOHNSTON, OF STATEN ISLAND, NEW YORK.

WOOD-SCREW MACHINE.

SPECIFICATION forming part of Letters Patent No. 282,107, dated July 31, 1883.

Application filed September 16, 1882. (No model.)

To all whom it may concern:

Be it known that I, EDWARD NUGENT, of Brooklyn, Kings county, New York, have invented certain new and useful Improvements 5 in Wood-Screw Machinery, of which the following is a specification.

My invention relates to machines for automatically cutting screw-threads upon blanks for screws, and more particularly to that class 10 of such machines known as "group screw-cutting machines."

My improvements, mainly, have reference first, to the hopper and means for delivering the blanks therefrom to the guideways; second, to the instrumentalities which regulate 15 the feed and delivery of the blanks to the clamping-jaws; and, third, to the mechanism by which the movements of the bars that carry the cutter-formers or pattern-cams and movable portions of the jaws are controlled; and 20 they, together with other features of my invention, can best be explained and understood by reference to the accompanying drawings, in which is represented a group screw-cutting 25 machine embodying my several improvements in their preferred form.

In the drawings, Figure 1 is a plan of a machine in which are grouped four sets of screw-cutting mechanisms. Two hoppers only are 30 represented, the other two, together with their supporting-frame and the rotating feed-fingers which work in them, being removed in order to disclose parts of the machine situated beneath them. Fig. 2 is a front elevation of 35 the machine with one of the cutter-stocks removed. Fig. 3 is a rear elevation of the machine. Fig. 4 is an elevation of that side of the machine on which is placed the cam which 40 controls the movements of the jaw-carrying and cutter-former bars and the blank receiving 45 and delivering arm. Fig. 5 is a section on line 55, Fig. 1. Fig. 6 is a horizontal section, partly in elevation, the plane of section passing just above the reciprocating cutter-carrier. In this figure a portion of the carrier is broken away so as to disclose one of the formers or patterns, together with that portion of the stock of the cutter that works 50 against it. Fig. 7 is a sectional front elevation, on an enlarged scale, of one set of clamping-jaws, together with the cutter and cutter-

stock and blank feeding and delivering mechanism which co-operate with said set of jaws. In this figure the parts are represented in the position which they occupy when the cutter 55 is operating on a blank contained in the jaws. Fig. 8 is a front elevation of the same parts in the position which they assume when the blank receiving and delivery mechanism has just delivered a blank to the stationary jaw 60 and the movable jaw is about to advance toward the other so as to close upon the blank. Fig. 9 is a diagrammatic figure representing a development of the cam which controls the movement of the former or pattern-bar and 65 the jaw-carrying bar.

Each of the four sets of screw-cutting mechanisms that compose the group is the counterpart of the others, both in construction and in mode of operation, so that a description 70 of one will answer for all.

A is the blank-holding hopper. It can best be understood by reference to Figs. 1 and 5. The blanks before being put into it have their heads finished and nicked. The bottom of the 75 hopper is curved from front to rear, and in it is formed a slot, *a*, which extends likewise from front to rear, and is at the front bounded by ridges *a'*, which gradually rise from the bottom of the hopper and meet the guideways *B*, between which the blanks from the hopper pass to the mechanism for cutting the screw-thread. The distance between the guideways is equal to the width of the slot *a*, and the width of the latter is such as to permit 80 only the shank or body of the blank to pass through it, so that blanks which may happen to fall therein will hang suspended by the head, as indicated in Fig. 5. Within the hopper, and in line with the slot, are one or more 85 fingers, *b*, which are attached to and project from a slowly-rotating shaft, 1, driven from any suitable source. In the arrangement shown in the drawings only one finger is employed to each hopper, which, in practice, I have 90 found will answer every purpose. The finger is placed eccentrically to the slot—that is to say, the slot is so formed, and the axis of rotation of the finger is so placed relatively thereto, that the finger will at the rear of the hopper enter or project into and through the slot 95 quite a distance, and will then, as it travels 100

toward the front of the hopper, gradually emerge from the slot until, as it reaches the point where the slot joins the ways B, its point will be out of the slot, or thereabout, and 5 tangential to the end of the ways, as indicated in Fig. 5, where it is represented in the act of lifting a blank by the head out of the slot into the passage formed by the guideways, its action being to tilt the blank over 10 the ends of the guideways into the passage between them, avoiding all contact with the blank, save at its head. When once the blank is fairly in the guideways the finger leaves it, and the blank descends, by force of gravity, 15 between the downwardly-inclined guideways to the point, whence it passes therefrom to the jaws. At the point where the guideways pass through the front of the hopper there is an opening above the guideways of sufficient size 20 to permit the passage of the head of the blank that hangs between them. I have found it essential, in order to prevent liability of the blanks choking or jamming in the slot during the operation of the machine, to give the finger a curved form substantially like that shown 25 in the drawings, by this means acting on the blanks which are in the slot with the point or tip only of the finger, and putting the rest of it in a position where it cannot interfere with 30 those blanks, and where it will keep the slot clean of others. The finger also acts as a stirrer during its passage through the mass of blanks in the hopper, thus causing one or more of them to fall into the slot, so as to be in 35 readiness for the finger when it next comes around.

In this class of machines the blank-receiving slot heretofore has been concentric with the axis of rotation of the finger, and this, of 40 course, I do not claim. My improvement in this direction is found in the eccentric arrangement of these parts, as above described, by which I obtain material advantages over the old arrangement, the finger acting on the 45 blank in the slot with greater ease and less liability of jamming, and also operating with entire certainty to tilt the blanks over the end of the slot into the guideways. The guideways extend downward in a sinuous path from 50 the hopper to a point just above the dies, and are so formed and arranged that at this point the blanks will lie point foremost, one above the other, in a horizontal plane or parallel with the dies, as indicated in Figs. 1, 2, 5, and 55 7, in which last-named figure the blanks are represented by dotted lines. The blanks are maintained in this position by a receiving and delivering mechanism, which feeds the blanks one by one, at the proper intervals, to the clamping-jaws. This mechanism, together with the 60 jaws, will now be described.

There are two jaws, C C'. The jaw C is stationary, and has in its face a half-round horizontal groove, c, which extends from front to 65 rear of the jaw. The jaw C' has a corresponding half-round groove, c'. It is mounted upon a slide-bar, D, which, by suitable mechanism,

has a reciprocating movement imparted to it at proper intervals, so as to move C' up to and away from the stationary jaw. When the two 70 come together, as indicated in Fig. 7, their two half-grooves, c c', meet and form a cylindrical hole of a size to receive and fit the shank of the screw-blank, the movable jaw C' being of a width from front to rear to embrace only that 75 portion of the shank which is to remain unscrew-threaded. The bar D is mounted in proper bearings, so as to be capable of sliding lengthwise, and is caused to reciprocate in this direction by mechanism which will be 80 hereinafter described.

The receiving and delivering mechanism consists of two parts, a vibratory or reciprocating blank-receiver, E, and a stop or cut-off, F, whose construction and arrangement 85 can best be seen in Figs. 1, 2, 4, 7, and 8. The receiver E is a hook-like arm which extends downward from the outer end of a rod, E', that is fastened to and projects forward from a rock-shaft supported in proper bearings in the frame of the machine. The receiver normally stands as shown in Fig. 7, in which position its bent or hook-like lower end extends across the end of the passage between the guideways B, so as to intercept and sustain the screw-blanks that lie therein. It will be noted here that the inner or acting vertical face of the stationary jaw C is in line with, or on prolongation of, the side of the passage opposite that on which the receiver is placed. 90 The receiver occupies this position so long as the jaws are closed. As soon, however, as the jaws are opened the receiver descends, and gradually lowering that blank which rests directly upon it guides it into the half-groove 95 in the stationary jaw, as seen in Fig. 8, and maintains it there until the movable jaw C' again moves up and closes around the blank, at which time it rises and resumes its first position. (Shown in Fig. 7.) There is no interference between the jaw C' and the receiver, for that jaw is of less length than the stationary jaw, and the receiver is situated so as to work in front of C', in connection with that portion of the stationary jaw C which extends farther to 100 the front than its fellow. It is requisite to prevent the mass of blanks above the lowermost one from following its movement when it is lowered by the receiver, as just explained, so that only one blank at a time and at proper 105 intervals shall be fed to the jaws. To this end I make use of the stop or cut-off F. This device consists of a horizontal cross pin or plate, which works through a hole in the guideways, and is mounted on the end of a spring-arm, 110 F', attached to the frame. This spring-arm has on it a swell or incline, d, and upon the vertical portion of the receiver is a projection, d', intended to act in connection with the swell or incline d. The distance between the cross-pin F and the bent lower end of the receiver is 115 about equal to the diameter of the screw-blank, so that when the lowermost blank rests upon the receiver the point of the cut-off or cross-

120

125

130

pin will stand opposite to the line of contact between that blank and the one next above, as indicated in Fig. 7. The cross-pin normally stands out of the path of the blanks, in the position indicated in the figure last referred to, with the projection d' just meeting the swell d . The consequence of this arrangement is that as soon as the receiver commences to descend, the cross-pin, by the action of the projection d' upon the swell d , will be shoved in against the stress of the spring-arm F' , so as to extend across the guideways and cut off all of the blanks save the lowermost one, thus permitting but one blank to be delivered by the receiver, and upholding the others, as indicated in Fig. 8, until the receiver resumes its original position, at which time the cut-off will return also to its first position (seen in Fig. 7) and permit the blanks to drop until they bring up against the receiver. This feed mechanism is very simple in construction and is entirely effective and certain in operation.

I now proceed to describe the mechanism by which the screw-thread is cut upon the blank held in the dies.

G is the cutter, and G' the cutter-stock. The cutter is placed in a recess or socket in the stock, and is there held by a cap, e . A stop gage, f , on the head of the stock is provided for the purpose of determining accurately the position of the cutter. The cap e is fastened in place by the screw e' . The cutter-stock is designed to vibrate upon a horizontal axis toward and away from the screw-blank in the dies, and for this purpose it is provided on its rear face with a horizontal projecting short stud or axle, g , (see Fig. 6,) mounted in bearings g' on a carrier bed or plate, H , which latter, by suitable mechanism hereinafter described, has imparted to it a reciprocating movement from front to rear, so as to impart the requisite transverse motion to the cutter. The vibrating movement of the cutter-stock is for the purpose of causing the cutter to approach and recede from the blank at proper times, and in order to cause the cutter to follow the taper of the blank I employ a pattern cam or former, I , mounted on a longitudinally-reciprocating bar, I' , to which proper movements are imparted by mechanism which will be presently described. The former I is intended to act on the tail or lower end of the stock G' , which is held against it by the stress of a spring, G^2 , as indicated in Figs. 2 and 6. The straight portion of the former is traversed by the stock while the cutter is working on the cylindrical part of the blank, and it traverses the inclined part of the former while working on the tapering point of the blank, as will be understood without further explanation. The cutter is intended to traverse the blank seven times for a screw of the size used in the illustration, cutting into it a little deeper each time, so as finally to cut a thread of the proper depth. For this purpose one end of the former-bar I is prolonged beyond the end of the machine, and has rigidly attached to this

end a rearwardly-extending arm, I^2 , Fig. 4, provided on its inner face with a stud or projection that works against an annular cam, J , 70 formed on the side of a power-driven revolving cam-wheel, J' . A spring, I^3 , serves to pull the bar in the direction requisite to hold the arm I^2 with yielding pressure against the cam. This cam is shown developed in Fig. 9.

There are seven rises, h h' h^2 h^3 h^4 h^5 h^6 , each a little in advance of its fellow, and seven intervening notches, i and i' . The rises h , &c., are the surfaces which act to hold the former-bar up in position for the cutter-stock. The six 80 notches i permit the bar at the conclusion of each forward movement of the cutter, during six of its traverses, to move to the left, (see Fig. 2,) far enough to allow the tail of the cutter-stock to move in like direction a distance 85 requisite to enable the cutter to clear the blank during the rearward movement of the stock. The seventh notch, i' , is deeper, and is intended, at the conclusion of the seventh and last cut, to permit the bar I^2 to move a greater distance 90 to the left for the purpose of withdrawing at this time the movable jaw C' , whose sliding bar D is connected with the former-bar by a lever mechanism, which can best be seen in Figs. 2 and 4. This mechanism consists of a two-part lever, K K' , hung on a pivot, j , on the frame of the machine. K is the main portion of the lever. It has its lower end forked, so as to straddle a pin, j' , on bar I^2 , and its upper end is situated between the machine-frame 95 and a downwardly-projecting lip or flange, D' , on the right-hand end of the bar D . With the upper end of the main portion of the lever is combined the other part, K' , which is held thereto by a headed red or bolt, k , passing 100 loosely through K , and having on that part of it which projects beyond K a spiral spring, k' , confined between the head of the rod and the lever. The part D' of the slide-bar D is held between K and K' , as shown. When the slide-bar I^2 is drawn out by one of the rises h , the jaw-carrying bar D is by the part K' pushed inward, so as to close the jaw C' against its fellow, and the movement is sufficient to carry the upper end of the lever part K some distance 105 away from D' , and to put the spring k' under considerable compression, as indicated in Fig. 2. Consequently when the arm I^2 drops into the shallow notches i the lever part K can move without disturbing the jaw-carrying bar D , which, by the action of the compensating springs k' on the part K' , is held firmly up in place; but when the arm drops into the deeper notch i' , then both jaw-carrying bar and former-bar will move simultaneously, so as to open the jaws and remove the formers from operative position.

By the combination with the cam-wheel and the former and jaw carrying bars of the two-part spring-lever, I am enabled to materially 110 simplify the machine and reduce the number of working parts.

The reciprocatory movements of the cutter carrier or plate H are imparted to it by scroll-

cams H' on a rotating shaft, 3, as indicated in Figs. 5 and 6. The carrier is held in yielding contact with these cams by a stiff retracting-spring, l , Fig. 6.

5 The rising-and-falling movement of the receiver E is obtained from the cam-wheel J' through the intermediary of an arm, E' , fixed to and projecting from shaft E^4 , and provided with a friction wheel or roller, E^5 , which is 10 held in contact with the periphery of the cam-wheel J' by a spring, m , as seen in Fig. 4. The cam-wheel has on its periphery a swell or rise, n , which acts to rock the shaft E' at the proper time during each revolution of the cam-wheel.

15 It now remains to describe what is known in machines of this class as the "screw-driving mechanism,"—that is to say, the mechanism by which the screw-blank is rotated during the time it is operated on by the cutter. This 20 mechanism is shown more plainly in Figs. 1 and 5. The screw-driver proper is a two-part driver consisting of the shank L and stem L' , which latter fits in a socket in the front end of the former and is pushed forward by a spring, o .

25 The stem is united to the shank by a cross-pin, p , whose ends extend into a short longitudinal slot, p' , in the shank. The stem is thus permitted to have a limited longitudinal movement independently of the shank, but both 30 must revolve together and in unison. The object of the former provision is to enable the point of the screw-driver to more readily find and enter the nick in the head of the screw-blank, in line with which the screw-driver is placed. The shank L is mounted in a rotary

35 power-driven tubular shaft or sleeve, M , with which it is connected by a pin-and-slot connection, $r r'$, similar to that shown at $p p'$, the object being to render the screw-driver capable of moving back and forth in the tubular sleeve by which it is rotated, so as to bring it into and out of engagement at proper times with the head of the blank. In order to impart to the screw-driver this back-and-forth 40 movement, the head of the shank L is formed

45 with an annular flange, s , which engages and runs in a groove, s' , in the top of a vibratory lever, N , pivoted to the machine-frame at t , and provided at its lower end with a stud or 50 teat that bears upon the periphery of a cam, N' , with which it is held in yielding contact by a spring, v . The cam is fixed on and revolves with a shaft, 4. In the upper end of 55 the lever N is a bearing-screw, w , which can be set up against the head of the screw-driver and is held in that position by a set-screw, x .

The shafting and driving-gearing may be briefly described as follows: The main or driving shaft is shown at 5. It communicates a 60 rapid movement of continuous rotation to the several screw-drivers through beveled gears 6 7. Shaft 3 is driven from shaft 5, through the intermediary of pinion 8 and spur-wheel 9. Shaft 4, on which are mounted both the cam-wheel J and the cams which operate the screw-driver levers, is driven from shaft 3 by pinion 10 and spur-wheel 11. The shaft 1 derives its

movement from shaft 3, through the intermediate pulleys, 12 13, and belt 14. The shaft 3 makes seven revolutions for each revolution of cam-wheel J . The parts are so proportioned, arranged, and timed in their movements relatively to one another as to operate in the following way: Suppose the last cut to have been made upon screw-blanks held in the dies and the arm I^2 to have just dropped into the deep notch i' of cam-wheel J . The effect will be to cause the jaws $C C'$ to open and release the finished screws, (which drop into the discharge spouts or chutes y ,) and simultaneously to move the former-bar 80 in a direction which will permit the cutter-stocks to turn on their pivots far enough to remove the cutters from the path of the blanks. The screw-drivers at the same time withdraw far enough to be disengaged from the nicks in 85 the heads of the screws. The receivers E now descend, and each lowers to its appropriate jaw C one screw, the others being retained during this time by the cut-offs F . As soon as this takes place the jaws C' move up and close upon 90 the blanks in the stationary jaws C , and simultaneously the former-bar moves to bring the formers up into operative position, and the cutter-carrier recedes to the point from which the cutters start to cut the thread, the receiver 95 E rising in time to clear the cutters, while by the time the cutters are in position to commence work the screw-drivers have advanced and found the nicks in the heads of the blanks, and the latter are consequently in rapid rotation in their jaws. The cutters now move forward and make the first cut, the depth of which is of course determined by the rise h on cam-wheel J' . The arm I^2 then drops into the first 100 notch, i , which permits the former-bar to move a little toward the left without disturbing the jaw-carrying bar, as hereinbefore explained, and simultaneously the cutter-carrier returns to its first position. By the second rise, h' , the former-bar is put in a position to cause the 105 cutters as they advance to make a deeper cut, and so on, progressively, until the final cut is completed, when the arm I^2 drops into the deep notch i' , and the operations hereinbefore described are repeated in the order recited.

110 It will be noted that in this group screw-cutting machine the cutter-stocks are placed side by side, parallel with one another, on a carrier which moves from front to rear of the machine, and also that the former and jaw carrying bars, the range of whose movement is comparatively short, move laterally, or from side to side of the machine. It will also be noted that each cutter-stock is mounted upon the carrier on its own pivot or axle, independently 115 of the others, and has its own separate former or pattern-cam. By this arrangement I am enabled to reduce the size of the machine and also to adjust and change any one of the cutter-stocks or formers without interfering with 120 or changing the adjustment of the others.

125 I have described what I believe to be the best embodiment of my invention; but it is manifest that the form and construction of the

parts may be varied considerably without changing the principle or mode of operation of the machine, and without departure from the spirit of my invention. I do not therefore restrict myself to the special construction herein shown and described; but

What I claim, and desire to secure by Letters Patent, is—

1. The hopper, provided in its curved bottom with a blank-receiving slot, in combination with the rotating feeding-finger placed eccentrically to the slot, substantially in the manner and for the purposes hereinbefore set forth.

15 2. The combination, substantially as hereinbefore set forth, of the hopper, provided in its curved bottom with a blank-receiving slot, the guideways having a passage between them forming a continuation of said slot, and the 20 rotating feeding-finger placed eccentrically to the slot and adapted to operate on the blanks contained therein, substantially as described.

3. The eccentrically-placed rotating feed-finger, curved as described, in combination 25 with the hopper provided in its curved bottom with a blank-receiving slot, substantially as hereinbefore set forth.

4. The combination, with the blank-holding jaws and the guideways or receptacle from 30 which the blanks pass to said jaws, of the receiver E, arranged and operating, substantially as described, to receive a blank from the guideways or receptacle and deliver it to the jaws, the combination being and acting substantially 35 as hereinbefore set forth.

5. The combination of the blank-holding jaws, the guideways or receptacle from which the blanks pass to said jaws, the receiver E, which receives and delivers to the jaws from 40 the guideways the lowermost blank contained in the latter, and the independent cut-off or

stop for sustaining in the guideways the other blanks while the receiver is delivering its blank to the jaws, these parts being arranged and having the mode of operation substantially as hereinbefore set forth. 45

6. The spring-controlled cut-off pin and the receiver, in combination with the guideways and the blank-holding jaws, for joint operation, substantially as hereinbefore set forth. 50

7. The jaw-carrying bar and the former-bar, in combination with the two-part spring-lever and its actuating cam-wheel, for joint operation, substantially as hereinbefore set forth.

8. The cam-wheel J', provided with a side cam for controlling the movement of the jaw-carrying bar and former-bar, and with a peripheral cam for actuating the receiver-carrying shaft, in combination with the jaw-carrying bar, the former-bar, the two-part spring-lever, and the receiver-carrying shaft, arranged and operating substantially as hereinbefore set forth. 55

9. The series of vibrating cutter-stocks, having independent axles, which extend from 60 front to rear of the machine and are mounted on a carrier which reciprocates in a similar direction, in combination with a corresponding series of jaws having their acting faces extending from front to rear, a series of independent formers or pattern-cams, one for each cutter-stock, and laterally-reciprocating jaw and former-carrying bars, these parts being timed in their movements relatively to one another, and adapted to co-operate substantially 65 in the manner hereinbefore set forth. 70

In testimony whereof I have hereunto set my hand this 2d day of September, 1882.

EDWARD NUGENT.
